KEY HOLDER

Thomas Gosselin, Attleboro, Mass., assignor to
Swank Products, Inc., a corporation of Delaware

Application April 1, 1938, Serial No. 199,392

11 Claims.

(Cl. 70—456)

This invention relates to key holders; and has for one of its objects to provide a key holder structure having a split construction of key retaining loop providing relatively movable sections in which the parts will be of simple formation and inexpensive of manufacture.

Another object of the invention is to provide a key ring of the above character in which mechanical means are employed for moving the split sections relative to each other to permit ready positioning or removal of a key.

Another object of the invention is the provision of a key holder having a split key retaining loop which will hold the keys in place yet be capable of limited movement of the loop parts relative to each other for ready positioning or removal of the key.

Another object of the invention is the provision of a means separate from the key retaining parts to influence separation or meeting of the parts and to provide a key retaining loop in the closed position of the parts.

Another object of the invention is the provision of means to positively move the split sections of the key retaining loop into separated or into connected relation, which means may be conveniently operated by a slight rotary motion between the thumb and finger of the user.

Another object of the invention is the provision of a closed key retaining loop of a sectional construction in which the parts are capable of relative movement toward and from each other and a means which actuates the sections is capable of positively holding the parts in separated or in connected relation.

Another object of the invention is the simplicity of the structure of the device and the presentation of an attractive appearance of the parts exposed to view.

Another object of the invention is a simple, detachable connection of the parts and yet one which is effective in their operation.

With these and other objects in view, the invention consists of certain novel features of construction, as will be more fully described, and particularly pointed out in the appended claims.

In the accompanying drawing:

Fig. 1 is a front view of a key holder constructed in accordance with my invention, showing the parts of the key loop in their connected or closed key retaining position;

Fig. 2 is a side edge view of the key holder shown in Fig. 1;

Fig. 3 is a front view of the key holder shown

in Fig. 1, certain of the parts being partly broken away to show the actuating mechanism;

Fig. 4 is a front view, partly in section, of the key holder shown in Fig. 3, showing the key retaining parts in a separated position for admitting the keys;

Fig. 5 is a cross-sectional view taken on the line 5—5 of Fig. 4 looking in the direction of the arrows;

Fig. 6 is a detail perspective view of one of the movable arm members forming one section of the main key retaining loop;

Fig. 7 is a detail perspective view of the head member to which are hinged the movable arm members;

Fig. 8 is a detail perspective view of the actuating screw for causing a separation or a meeting of the movable arm members;

Fig. 9 is a detail perspective view of the rotatable nut for causing reciprocation of the actuating screw.

It is desirable in key holders of the type having a closed key retaining loop construction to provide some structure which will permit the ready positioning or removal of one or more of the individual keys without interfering with the order of the other keys in the group held on the key retaining member, and to detach whatever key

may be selected without the necessity for removing a considerable number of the keys carried upon the key loop; and in order to provide an extremely simple device for satisfying this desired result, I have provided a key holder structure in which the key retaining loop is of a separable or split construction and formed of two

hinged arm members which are so constructed and arranged that they are relatively movable to bring their free ends into separated or into connected relation when putting keys on and off the key loop, and these free end portions of the arm members are bent transversely thereof to provide inwardly extending portions so arranged

that their terminal ends will be substantially aligned and connected in the closed position of the arm members for providing the transverse hanger member on which the keys are carried; and I have further provided means at the end of one of the extensions of which the hanger member is formed so arranged that it will have

interfitting engagement with the terminal end of the corresponding extension of the opposite arm member when in their closed position to form a closed key loop; and I have further provided positive mechanical means in the form of a rotary member separate from the arm members of the

split loop acting at the hinged ends of the same and capable of manual operation by frictionally turning between the flesh of the thumb and a finger of the user and rotated to cause relative 5 rocking movement of the loop sections into a separated or into a connected position to open and close the same as desired; and the following is a more detailed description of the present embodiment of this invention, illustrating the preferred means by which these advantageous results may be accomplished.

With reference to the drawing, 10 designates generally the novel key holder structure and comprises a head 11 which may be of any desired 15 contour and formed either of cast metal or a metal stamping. The head 11 is provided with an enlarged bottom portion 12 from which depends the main key carrying loop as indicated generally at 13 which in the form shown is of a 20 split or separable construction forming a closed loop of stirrup-shaped outline, but is not limited to such contour as it may have the general form of a partial ring or comprise a member having other common geometric shapes.

25 As shown in Figs. 1 to 4 of the drawing, the key retaining loop 13 is made up of two sections and comprises two oppositely disposed arm members 14 and 15 which are pivotally attached at their upper ends to the lower part of the enlarged portion 12 of the head 11 of the key holder at oppositely disposed positions thereof, by means of the pivot pins 16 and 17 respectively, passing through suitable holes 18 and 19 formed in the respective arm members, so that the latter are relatively 30 movable with reference to each other in the same plane so as to bring the free ends of the arm members into separated or into connected relation with each other for providing a key opening at one time and a closed key loop at another time. 35 The arm members 14 and 15 may be formed of suitable material and be of any desired cross-sectional shape, but in the present construction each is shown as being formed of solid metal of round cross-section. The arm members 14 and 40 15 are each of substantially the same construction except at their free ends, so that it is only necessary to describe but one of such members, thus in Fig. 6, the arm member 14 is shown as having an upper portion 20 bent to present an arcuate outline curving progressively downwardly from the 45 pivot end of the arm member to form one side wall of a stirrup-shaped key loop. The lower end of the arcuate arm portion 20 is transversely bent as indicated at 21 to provide the inwardly extending hanger portion 22, the terminal end of 50 which is provided with a stud portion 23 which is so arranged and of such shape that it will enter and have interfitting engagement with a correspondingly shaped opening 24 formed in the 55 terminal end face of the cooperating hanger extension 25 of the opposite arm member 15 when in the closed position of the arm members, as shown in Figs. 1 and 2.

The enlarged portion 12 of the head 11 is provided with a channel 26 extending lengthwise of its undersurface to receive the U-shaped ears 27 and 28 which are struck out of the flattened stock of the pivot end portions of the arms 14 and 15 respectively, as shown in Figs. 3 and 4. 60 The head 11 also is provided with a central bore 30 extending axially thereof at right angles to the channel 26 and communicating therewith to form a guideway for a reciprocable screw 31 having a flanged portion 32 which is disposed 65 within the channel 26 and projects into the U- 70

shaped ears 27 and 28 of the arm members 14 and 15 to have connection therewith at diametrically opposite positions of the screw 31. A rotary nut 33 disposed within an enlarged opening 34 formed laterally of the head 11, has screw threaded opening 35 for connection with the threads on the shank of the screw 31 and provides a means for reciprocating the screw longitudinally of the bore 30 in order to positively move the arm members 14 and 15 about their pivots simultaneously 10 into open or into closed position.

In use, the arm members 14 and 15 normally are in closed position, as shown in Fig. 1, with one or more of the keys carried in a suspended position by the bottom cross arm of the key loop 15 formed by connection of the respective extensions 22 and 25 of the arm members 14 and 15. When it is desired to remove a key from the key loop or to place another key thereon one simply slides the different keys which are to be retained to a location at one side of the split and then manipulates the rotary nut member 33 between his thumb and forefinger in the proper direction to force the screw 31 inwardly or downwardly of the bore 30 and consequently move the head portion 32 sufficiently to swing the arm members 14 and 15 outwardly to separate their free ends, thereby providing a space between the terminal ends through which the desired key or keys may be passed to admit them to or to withdraw them from the cross bar extensions 22 and 25 respectively. If it is desired to position a key, the procedure then is reversed, in which instance the arm members 14 and 15 are first separated to provide a key opening through which the key is 35 passed and placed on either of the cross bar extensions 22 or 25, after which the rotary member 33 is manipulated as above explained but in the opposite direction to draw in the screw 31 outwardly or downwardly of the bore 30 and move 40 the arm members 14 and 15 together with their free ends into interfitting connection to provide the closed key loop.

The member 33 operates with sufficient friction so that it will not accidentally turn or rotate when 45 in the pocket, thus rendering it substantially impossible for the keys to be removed except by manipulation of the rotary nut. A ring 36 passed through a suitable hole 37 formed in the top end of the head 11 serves for attachment of the key 50 holder to a chain, swivel hook or other suitable means, as is usual in devices of this character, for fastening the keys to part of the clothing of the user.

The foregoing description is directed solely 55 towards the construction illustrated, but I desire it to be understood that I reserve the privilege of resorting to all the mechanical changes to which the device is susceptible, the invention being defined and limited only by the terms of the appended claims.

I claim:

1. A key holder comprising a key retaining loop split to provide two sections, the corresponding end portions of said section being in contactable relation, and the opposite end portions of each loop section being hingedly related so as to provide for the relative movement of one section toward and from the other, and means to cause such relative movement.

2. A key holder comprising a closed key retaining loop formed in two sections each of which is pivoted at one end and both being relatively movable to bring their free ends into separated or into connected relation to permit the ready

positioning or removal of a key and retention of the same, and means acting on said sections for causing a relative movement of the same to opened or to closed position.

5 3. A key holder comprising a closed key retaining loop formed in two sections each of which is pivoted at one end and both being relatively movable to bring their free ends into separated or into connected relation to permit the ready 10 positioning or removal of a key and retention of the same, and reciprocable means separate from said sections and acting thereon to cause such relative movement into opened or into closed position.

15 4. A key holder comprising a head, two members pivoted at one end to said head and relatively movable to bring the free end portions into separated or into abutting relation for forming a closed key retaining loop when in the abutting 20 position, a movable member having a portion connected with each of said pivoted member, and means for moving said movable member for causing a relative movement of said pivoted members into separated or into closed position.

25 5. A key holder comprising a head, two members pivoted at one end to said head and relatively movable to bring the free end portions into separated or into connected relation for forming a closed key retaining loop when in the connected 30 position, a reciprocable member having a portion connected with each of said pivoted members, and means for reciprocating said member for causing a relative movement of said pivoted members into separated or into closed position, and means on said head for the attachment of a chain or the like.

35 6. A key holder comprising a head, two generally curvilinear arm members pivoted at one end to said head and relatively movable to bring the free end portions into separated or into connected relation for forming a closed key retaining loop when in the connected position, a movable member having a portion connected with each of said pivoted members, and rotary means separate from said arm members and movably secured to said movable members for manually moving said movable member for causing a relative movement of said pivoted members into separated or into closed position.

40 7. A key holder comprising a head, two arm members hinged at one end to said head and relatively movable to bring the free end portions into separated or into connected relation for forming a closed key retaining loop in the connected position of said members, a screw having an enlarged portion connected with each of said arm members, a guideway for said screw, and means positioned in said head for manually reciprocating said screw in said guideway for causing relative movement of said hinged arm members into closed or into open position.

45 8. A key holder comprising a head provided with a channel, two depending arm members in said channel, each arm member being hinged at one end to said head and relatively movable to bring the free end portions into separated or into

5 connected relation for forming a closed key retaining loop in the connected position of said members, a screw having an enlarged head connected with each of said members at oppositely disposed points, a guideway in said head for said screw, and rotary means positioned in said head for manually reciprocating said screw in said guideway for causing relative movement of said hinged members into closed or into open position.

10 9. A key holder having a split key-retaining 15 loop structure comprising a pair of arm members hingedly connected at one end and relatively movable to bring the free ends thereof into separated or into connected relation with each other, the free end portions of each of the members being bent transversely thereof to form inwardly extending portions so arranged that their terminal ends will be aligned and interlocked in the closed position of the arm members to form a unitary key supporting member yet provide a key 20 admitting opening in the separated position of the members for the ready positioning or removal of a key, and means acting on said members for causing a relative movement of said members to effect a separation or a union of the free end 25 portions of said extensions.

15 10. A key holder having a split key-retaining 30 loop structure comprising a pair of arm members hingedly connected at one end and relatively movable to bring the free ends thereof into separated or into connected relation with each other, the free end portions of each of the members being bent transversely thereof to form inwardly extending portions so arranged that their terminal ends will be aligned and connected in the 35 closed position of the members to form a unitary key supporting member yet provide an opening therebetween in the separated position of the members for the ready positioning or removal of a key, and means acting on the hinged end 40 portion of said members to exert pressure thereon for causing a relative movement of said members to effect a separation or a contacting relation of the free end portions thereof.

45 11. A key holder comprising a head having an enlarged lateral opening intermediate the ends thereof and provided with a channeled end and a bore extending between said channel and said opening, two depending arm members pivoted at one end in said channel located at oppositely disposed points thereof and relatively movable to bring the free end portions into separated or into connected relation for forming a closed split 50 key retaining loop in the connected position of said arm members, a screw reciprocably mounted in said bore and having a portion connected with each of said arm members at the hinged end portions thereof, a rotary member carried by said screw and mounted within said lateral opening in said head for reciprocating said screw, when 55 manually rotated for causing simultaneous movement of said arm members toward or away from one another so as to bring the free end portions of the arm members into closed or into separated position.

60 65 THOMAS GOSELIN.
